UNITED STATES PATENT OFFICE.

WILLIAM C. GREGG AND LOUIS D. GREGG, OF HACKENSACK, NEW JERSEY, ASSIGNEES
TO THE GREGG COMPANY, LIMITED, OF HACKENSACK, NEW JERSEY, A CORPOR-
ATION OF NEW YORK.

RAILWAY-TIE AND FASTENER.

1,230,703.

Specification of Letters Patent. Patented June 19, 1917.

Application filed September 23, 1916. Serial No. 121,725.

To all whom it may concern:

Be it known that we, WILLIAM C. GREGG and LOUIS D. GREGG, citizens of the United States, residing at Hackensack, in the county of Bergen and State of New Jersey, have invented certain new and useful Improvements in Railway-Ties and Fasteners; and we do declare the following to be a full, clear, and exact description of the invention, such as will enable others skilled in the art to which it appertains to make and use the same, reference being had to the accompanying drawings, and to the letters and figures of reference marked thereon, which form a part of this specification.

Our invention relates to railway tie fasteners, and has for its object to provide a fastener simple in construction, easy of application, and efficient in securely clamping the rail and tie together and preventing movement of one relatively to the other. To the accomplishment of the foregoing and such other objects as may hereinafter appear the invention consists in the features of construction hereinafter particularly described and then sought to be clearly defined by the claims, reference being had to the accompanying drawing forming a part hereof and in which—

Figure 1 is a plan view of portions of a tie and rail having the improved fastener applied;

Fig. 2 is a central cross section through a rail and tie, with the features shown in full lines;

Fig. 3 is a front elevation of the novel shaped clip that fits on one end of the clamping bolt.

In the drawing the numeral 1 designates a metal cross tie which may be of any approved type of construction but for simplicity is shown as a flat piece of metal, and upon which the rail 2 rests. The fastener consists of a bolt 3 which lies beneath and in contact with the under face of the tie and is formed at one end with a hook or claw 4 which passes up through an opening 5 in the tie and overlies the bottom flange of the rail 2. The opposite end of the bolt 50 carries a novel construction of clip or claw which overlaps the adjacent flange of the rail and embraces the rail and tie and has oppositely disposed shelves or brackets which project inwardly under the tie at 55 both sides of the clamping bolt so that the

bolt and shelves will both bear against the under face of the tie and thus afford additional strength to the tie beneath the rail and distribute the strains through both the tie and clamping bolt without throwing undesirable strains on either. This clip or claw designated by the numeral 5' is formed with a bolt hole 6 for the passage of the clamping bolt 3 and at each side of the hole 6 is formed a shelf or bracket 7 which extends inwardly beneath and in contact with the under face of the cross tie 1, and its inner faces 8 are preferably made to conform to the exterior lines of the clamping bolt so as to hug snugly to the sides thereof whereby an extended bearing for the clip is afforded by the clamping bolt. The clip is also provided with the upper claw 9 which will lap over onto the top of the rail flange, the portion of the clip between the lower shelves and upper overhanging claw receiving and forming an abutment for the tie and edge of the rail flange. The tie is formed with an opening 10 for the clip to extend up over the rail flange and for the application of a wrench or other tool to the nut 11 which fits on the threaded end of the clamping bolt.

By forming the clip 5' so that it may be applied as described, it will be observed that the rail and tie are securely clamped together when the nut 11 is screwed up; that the tie is braced and strengthened by the clamping bolt and the shelves of the clip bearing against the under-side of the tie; and that the clamping bolt is relieved of strains that would tend to bend or distort the same; and that when the sides of the shelves are made to conform to the exterior lines of the clamping bolt the latter will afford an extended bearing for the clip. Changes in the particular form of the parts described may be made and essential features of the invention retained.

Having described our invention and set forth its merits, what we claim is:

1. A railway tie and fastener comprising a tie, a clamping bolt having a claw at one end to grip the flange of a rail, and a clip for the other end of the bolt formed with a claw to grip the rail flange and an opening for the bolt and having oppositely disposed shelves extended in the direction of the claw to lie below the rail flange and bear against the under face of the tie and spaced apart to 110

lie at opposite sides of the bolt to permit the bolt to lie close to the under face of the tie.

2. A railway tie and fastener comprising a tie, a clamping bolt having a claw at one end to grip the flange of a rail, and a clip for the other end of the bolt formed with a claw to grip the rail flange and an opening for the bolt, and having inwardly projecting shelves at opposite sides of the bolt 10 opening, to bear against the under face of the tie at opposite sides of the bolt, the inner

faces of the shelves conforming to the outline of the bolt to have an extended bearing afforded by the bolt for the clip.

In testimony whereof we affix our signatures in presence of two witnesses. 15

WILLIAM C. GREGG.
LOUIS D. GREGG.
